Specification for Design.

Patented Feb. 8, 1921.

Application filed November 21, 1919. Serial No. 339,734. Term of patent 14 years.

To all whom it may concern:

Be it known that I, WILLIAM C. HAAG, a citizen of the United States, residing at Lowell, in the county of Middlesex and State of Massachusetts, have invented a new, original, and ornamental Design for a Sign, of which the following is a specification, reference being had to the accompanying drawings.

In the accompanying drawings, Figure 1 is a front view of a sign embodying the features of the new design, and Fig. 2 is a right hand end view of the sign shown in Fig. 1.

I claim:

The ornamental design for a sign, as shown.

WILLIAM C. HAAG.
